RADIO SPEED KEY

John R. Pinelli, United States Navy

Application May 27, 1942, Serial No. 444,748

11 Claims. (Cl. 178—82)

(Granted under the act of March 3, 1883, as amended April 30, 1928; 370 O. G. 757)

This invention relates in general to telegraph keys for code sending and particularly to those of the so-called "high speed" type utilizing a manually operated key lever which is shifted in one direction to form "dashes." When the key lever is shifted in the other direction, a series of "dots" are formed by a vibrator lever coupled to and set in motion by the key lever.

An object of the invention is to provide a novel construction for a speed telegraph key in which motion imparted to the key lever is transmitted to a vibrator lever which is pivoted to the key lever in such a manner as to set up a vibration of large amplitude in the vibrator lever.

Another object of the invention is to provide a speed telegraph key in which motion imparted to the key lever is transmitted to the vibrator lever in such a manner as to impart a considerable "whipping" action to the latter lever.

Another object of the invention is to provide a speed telegraph key which by virtue of its novel construction, employing a key lever having a bifurcated portion and within which a vibrator lever operates, produces a structure which is considerably shorter than speed keys now known in the art.

A more specific object of the invention is to provide a speed telegraph key in which a pivotedly mounted vibrator lever carrying a contact and utilized for making "dots" by intermittent engagement with a stationary contact is quickly damped to an inoperative rest position when the key is moved from its "dot" making position by resilient means acting on the lever about its pivot thereby preventing the operator from sending "dots" unintentionally.

With the foregoing and other objects in view, which will become apparent as the description proceeds, the invention resides in the combination and arrangement of parts and in the details of construction hereinafter described and claimed, it being understood that changes in the precise embodiment of the invention herein disclosed can be made within the scope of what is claimed without departing from the spirit and scope of the invention.

The invention is illustrated in its present embodiment in the accompanying drawing in which like parts are designated by like reference characters in the several views.

Fig. 1 is a plan view showing the key in a neutral position; Fig. 2 is a view showing the key in both its "dot" and "dash" positions; and

Fig. 3 is a side elevational view together with a schematic diagram of the electrical circuit through the component parts of the key.

Referring now to Figs. 1, 2 and 3, 1 is a base member and is provided with an upstanding L shaped member 2. A pair of pivots 3 and 4 are provided for pivotally supporting a key lever 5

having a bifurcated portion comprising the tines 6 and 7, and a "finger" piece 8.

A pivot pin 9 connects the open ends of the tines 6 and 7 and is provided for pivotally supporting a vibrator lever 10 for operation between tines 6 and 7. The lever 10 consists of a pivoted member 11 and a vibrating member 12 connected together by a resilient member such as a flat spring member 13.

10 The vibrating member 12 of lever 10 is provided with the usual weight member 14 which may be adjusted axially of member 12 to any desired position and locked in such position by means of a set screw 15. The position of the 15 weight 14 will obviously vary the characteristics of vibration of member 12 and will depend somewhat upon the particular desires of the operator.

Member 11 is bored horizontally at one end thereof and a screw 16, the shank of which is 20 preferably of smaller diameter than the said bore, is inserted through the bore and threaded into a post 17 supported on the base 1. A spring 18 is carried on screw 16 and is disposed in compression between the faces of member 11 and post 17. Spring 18 functions to restore the key lever 5 to a neutral position when released from a "dash" making position. A lock nut 19 is provided for adjusting the position of screw 16.

A second post 20 is supported on base 1, and 30 a screw 21, the position of which is also made adjustable by means of a lock nut 22, acts as a stop member to limit pivotal movement of member 11. A spring 23, carried on screw 21 is disposed in compression between the faces of member 11 and post 20 and functions to restore vibrator lever 10 to a neutral position upon release of the key lever. It will be apparent that spring 23 by pressing against member 11 acts to bias the end of vibrating member 12 of vibrator lever 10 against 35 a conventional, loosely mounted damper and stop member 24. Spring 18 also serves to bias member 12 against stop member 24 since springs 18 and 23 lie on opposite sides of the pivot pin 9.

40 A U shaped resilient member 25 supported on the vibrating part 12 carries a contact 26 which is adapted to intermittently engage a complementary stationary contact screw 27 which threads through a post 28 and makes "dots." A lock nut 29 secures contact screw 27 in any desired position.

45 For making "dashes," a contact 29 carried by the key lever 5 is adapted to engage a complementary contact screw 30 which threads through a post 31. A lock nut 33 secures contact screw 30 in any desired position.

50 Insulating washers 34 are utilized to insulate each of the posts 28 and 31 from the base 1. To connect the key in an electrical circuit, a pair of conductors 38 and 39 which may be united outside of the key in a common sleeve 35 are brought

into the interior of the base 1. Conductor 38 splits into two branches, one branch 37 being connected to post 28 and the other branch 36 being connected to post 31. Conductor 39 is connected directly to L member 2.

Thus when key lever 5 is moved to the position shown in full lines in Fig. 2, contacts 26 and 27 are intermittently engaged as previously described and a path for current flow is established upon engagement between contacts 26 and 27 through conductors 38 and 39. This path may be traced from conductor 39 through L member 2, pivot 3, fork 6 of key lever 5, pivot pin 9, vibrator lever 10 to contact 26, contact screw 27, post 28 and conductor 37 to the conductor 38. When key lever 5 is moved to the position shown in broken lines in Figure 2, and contact 29 is engaged with contact screw 30, a path is also established for current flow between conductors 38 and 39. This latter path may be traced from conductor 39 through L member 2, pivot 3, fork 6 of key lever 5, contact 29, contact screw 30, post 31 and conductor 36 to conductor 38.

Operation

The operation of my improved speed-key is as follows:

In order to send out one or more "dots," the operator will move the finger piece 8 in the direction of the solid arrow. This movement will cause pivotal action of the key lever 5 about its pivots 3 and 4. Vibrator lever 10 is pivoted to the tines 6 and 7 of the key lever by pivot pin 9 and will also move with the key lever 5. When the end of the pivoted part 11 of the vibrator lever 10 strikes the head of the screw 16 and is stopped thereby, a sudden pivotal movement is imparted to the pivoted part 11 about pivot 9 which imparts a "whipping" action to the vibrating part 12 and weight 14 carried thereby which sets up vibration therein thus effecting an intermittent engagement of contact members 26 and 27. This "whipping" action is increased due to the fact that when the end of member 11 is stopped, the pivot pin 9 is still moving. Stop member 21 serves to limit pivotal movement of the pivoted part 11 and in doing so produces an initial vibration of considerable amplitude in member 12.

In order to send out a "dash," the operator will move the finger piece 8 in the direction of the broken arrow. This movement will turn key lever 5 on its pivots 3 and 4 in the opposite direction to effect engagement between contact members 29 and 30.

The invention described herein may be manufactured and used by or for the Government of the United States of America for governmental purposes without the payment of any royalties thereon or therefor.

Having now fully described my invention, what I claim is:

1. A code transmitting instrument of the automatic dot type comprising, a horizontal base plate, a key lever, pivot means engaging a medial portion of said key lever for mounting said key lever on said base plate for horizontal swinging movement, a vibrator lever pivotally mounted on the said key lever for horizontal movement by a vertically disposed floating pin joint common to both levers, said pin joint being disposed at one end of said key lever, and a pair of adjustable stops, said stops being disposed on opposite sides of the said pin joint and on the same side of the said vibrator lever, whereby one coacts with said vibrator lever on one side of said pin joint to

thereby impart a flexing couple to the said vibrator lever and the other limits the resulting motion.

2. In a code transmitting instrument, a support, a hand operated "dash" and "dot" lever, pivot means engaging a medial portion of said hand operated lever for mounting the same on said support for horizontal swinging movement, a vibratory lever, second pivot means connecting one end of said hand operated lever to an intermediate portion of said vibratory lever, "dot" contact means carried by said vibratory lever on one side of said second pivot means, and a pair of stop means, the first of said stop means being adapted to abut said vibratory lever on the other side of said second pivot means as said hand operated lever is moved to a "dot" position whereby said vibratory lever will be caused to turn on said second pivot means and abut the second of said stop means to intermittently operate said "dot" contact means.

3. A code transmitting instrument comprising a support, a key lever, first pivot means carried by said support and which engage said key lever intermediate the ends thereof, a vibrator lever, second pivot means connecting said key lever to said vibrator lever intermediate the ends thereof, "dot" contact means carried by said vibrator lever on one side of said second pivot means and a pair of stop means, the first of said stop means being adapted to abut said vibrator lever on the other side of said second pivot means as said key lever is turned on said first pivot means to a "dot" position whereby said vibrator lever will be caused to turn on said second pivot means and abut the second of said stop means to intermittently operate said "dot" contact means.

4. A code transmitting instrument comprising a support, a key lever including a "dash" contact means, first pivot means carried by said support and which engage said key lever intermediate the ends thereof, a vibrator lever, second pivot means connecting said key lever to said vibrator lever intermediate the ends thereof, "dot" contact means and a weight member carried by said vibrator lever on one side of said second pivot means, first and second stop members, said first stop member being adapted to abut said vibrator lever on the other side of said second pivot means as said key lever is turned on said first pivot means to a "dot" position whereby said vibrator lever will be caused to turn on said second pivot means and abut said second stop member to intermittently operate said "dot" contact means, a third stop member adapted to abut said vibrator lever on the side thereof carrying said weight member and means for biasing said vibrator lever into abutment with said third stop member as said key lever is turned to a "dash" position to actuate said "dash" contact means.

5. A code transmitting instrument comprising a support, a key lever, first pivot means carried by said support and which engage said key lever intermediate the ends thereof, a vibrator lever, second pivot means connecting said key lever to said vibrator lever intermediate the ends thereof, a "dot" contact means carried by said vibrator lever on one side of said second pivot means, a pair of stop means, the first of said stop means being adapted to abut said vibrator lever on the other side of said second pivot means as said key lever is turned on said first pivot means to a "dot" position whereby said vibrator lever will be caused to turn on said second pivot means in

one direction and abut the second of said stop means to intermittently operate said "dot" contact means, and resilient means disposed on each side of said second pivot means, each of said resilient means being arranged to exert the restoring force therein against said vibrator lever in opposite directions to cause said vibrator lever to turn on said second pivot means in the other direction.

6. A code transmitting instrument comprising a support, a key lever, first pivot means carried by said support and which engage said key lever intermediate the ends thereof, a vibrator lever, said lever comprising a rigid support portion and a vibratory portion, second pivot means connecting said key lever to the rigid portion of said vibrator lever, "dot" contact means and a weight member carried by the vibratory portion of said vibrator lever on one side of said second pivot means, and a pair of stop means, the first of said stop means being adapted to abut the rigid portion of said vibrator lever on the other side of said second pivot means as said key lever is turned on said first pivot means to a "dot" position whereby said vibrator lever will be caused to turn on said second pivot means to bring the rigid portion thereof into abutment with said second stop means and effect vibration of the vibratory portion thereof to produce an intermittent operation of said "dot" contact means.

7. A code transmitting instrument comprising a support, a key lever including "dash" contact means, first pivot means carried by said support and which engage said key lever intermediate the ends thereof, a vibrator lever, said lever comprising a rigid portion and a vibratory portion, second pivot means connecting said key lever to the rigid portion of said vibrator lever, "dot" contact means and a weight member carried by the vibratory portion of said vibrator lever on one side of said second pivot means, means for adjusting the position of said weight member along the axis of said vibratory portion, stop means adapted to abut the rigid portion of said vibrator lever on each side of said second pivot means whereby as said key lever is turned on said first pivot means to a "dot" position said vibrator lever will abut one of said stop means and be caused to turn on said second pivot means and then abut the other of said stop means to thus initiate vibration of the vibratory portion thereof to produce an intermittent operation of said "dot" contact means, a stop member carried by said key lever, and means for biasing said vibratory portion into abutment with said stop member as said key lever is turned on said first pivot means to a "dash" position to operate said "dash" contact means.

8. A code transmitting instrument comprising a support, a key lever, said lever including a finger piece, a bifurcated portion and "dash" contact means, first pivot means carried by said support and which engage said key lever intermediate the ends thereof, a vibrator lever, second pivot means carried by said bifurcated portion and which engage said vibrator lever intermediate the ends thereof to permit pivotal movement of said vibrator lever, "dot" contact means and a weight member carried by said vibrator lever on one side of said second pivot means, means for adjusting said weight member axially of said vibrator lever, a first stop member adapted to abut said vibrator lever on the other side of second pivot means as said key lever is turned on said first pivot means to a "dot" position whereby said vibrator lever will be caused to turn on said sec-

ond pivot means a second stop member adapted to abut and stop the turning movement of said vibrator lever thereby initiating vibration of the latter to intermittently operate said "dot" contact means, a third stop member carried by said key lever and adapted to abut said vibrator lever on the side thereof carrying said weight member, and means for biasing said vibrator lever into abutment with said third stop member as said key lever is turned to a "dash" position to operate said "dash" contact means.

9. The combination in claim 8 wherein the portion of said vibrator lever carrying said "dot" contact means and said weight member is operable between said bifurcated portion of said key lever.

10. A code transmitting instrument comprising a support, a key lever including a finger piece, a bifurcated portion and "dash" contact means, first pivot means carried by said support and which engage said key lever intermediate the ends thereof, a vibrator lever including a rigid portion and a vibratory portion, second pivot means connecting the bifurcated portion of said key lever to the rigid portion of said vibrator lever, "dot" contact means and a weight member carried by the vibratory portion of said vibrator lever on one side of said second pivot means for operation within the bifurcated portion of said key lever, means for adjusting the position of said weight member along the axis of said vibratory portion, a first stop member adapted to abut the rigid portion of said vibrator lever on the other side of said second pivot means as said key lever is turned on said first pivot means to a "dot" position whereby said vibrator lever will be caused to turn on said second pivot means a second stop member adapted to abut and stop the turning movement of said vibrator lever thereby initiating vibration of the vibratory portion thereof to produce an intermittent operation of said "dot" contact means, a third stop member carried by said key lever and adapted to abut the vibratory portion of said vibrator lever, and means for biasing said vibratory portion into abutment with said third stop member as said key lever is turned on said first pivot means to a "dash" position to operate said "dash" contact means.

11. A code transmitting instrument of the automatic dot type comprising, a horizontal base plate, an operating key lever pivoted thereon for horizontal motion, a vibrator lever having a horizontal bore therein and pivoted to said key lever for horizontal motion with and relative to said key lever by a horizontally movable floating hinge joint, a post mounted on the said base plate, a set screw having a head portion of a diameter greater than that of the bore in the vibrator lever and a shank portion of a diameter less than that of the bore, said screw being inserted through said bore and being screwed into said post, a coiled compression spring disposed upon said set screw and located between the said post and the said vibrator lever for biasing said vibrator lever into engagement with the head of the said set screw whereby on operation of the said key lever the said set screw head acts as an adjustable fulcrum and coacts with the said floating hinge joint to impart a pivotal movement of said vibrator lever, and a second post mounted on the said base plate and having an adjustable set screw therein for arresting pivotal movement of said vibrator lever.

JOHN R. PINELLI.
